UNITED STATES PATENT OFFICE.

JOHN H. DORAN, OF SCHENECTADY, NEW YORK, ASSIGNOR TO GENERAL ELECTRIC COMPANY, A CORPORATION OF NEW YORK.

ELASTIC-FLUID TURBINE.

1,294,245.

Specification of Letters Patent. Patented Feb. 11, 1919.

Application filed October 17, 1917. Serial No. 197,158.

To all whom it may concern:

Be it known that I, JOHN H. DORAN, a citizen of the United States, residing at Schenectady, in the county of Schenectady, 5 State of New York, have invented certain new and useful Improvements in Elastic-Fluid Turbines, of which the following is a specification.

In elastic fluid turbines of large sizes, the 10 volume of the motive fluid becomes very great in the last stages, and the problem of providing bucket areas sufficiently large to handle it efficiently is an important one, the permissible length of buckets being limited 15 due to mechanical reasons as is well known. One arrangement for accomplishing this is to build the low pressure portion of the machine in two sections between which the elastic fluid is divided and through which it 20 passes in parallel, and the object of the present invention is to provide an improved arrangement or structure in a turbine of this type.

For a consideration of what I believe to be 25 novel and my invention, attention is directed to the accompanying specification and claims appended thereto.

In the drawing the figure is a longitudinal 30 sectional view of a turbine embodying my invention.

Referring to the drawing, 5 indicates a turbine shaft, 6 the bucket rings of a high pressure turbine section, and 7 and 8 the bucket rings of a divided low pressure turbine section. In the present instance, the bucket rings 6 are shown as being carried by a drum 9 suitably mounted on the shaft, but it will be understood that they may be carried by suitable wheels if found desirable. 40 Surrounding the bucket rings 6 is an inner casing 10 which carries the stationary intermediates 11 of the high pressure turbine section. In the case of an impulse turbine these will be of course in the form of suitable nozzles. 12 indicates suitable packings for preventing leakage between the drum 9 and the intermediates 11. Surrounding the casing 10 at its high pressure end is a wall 13 forming an elastic fluid chest 14 from 45 which motive fluid is fed by annular passage 15 to the first ring of intermediates 11. The arrangement it will be noted is for complete peripheral admission. One or more conduits as indicated at 16 may be used to supply elastic fluid to the chest 14. At 17 is a

labyrinth packing which acts to prevent leakage of motive fluid and also to balance the end thrust of the machine. The stationary elements of packing 17 are carried by an annular plate 18 fixed to casing 10 and the 60 rotating elements by an annular ring 19 bolted to the drum 9.

Each part of the divided low pressure section is shown as comprising a single ring of buckets, the ring 7 being carried by a wheel 65 20 and the ring 8 by a wheel 21, such wheels being located close up to and one on each side of the drum 9. Surrounding the inner casing 10 is an outer casing 22 spaced from and connected to the inner casing by webs 70 23. In other words, the inner casing 10 is supported in spaced relation to the outer casing 22 by the webs 23. Carried by the outer casing 22 are two rings of intermediates or nozzles 24 and 25 for directing 75 elastic fluid to the bucket rings 7 and 8. The space between the two casings 10 and 22 forms a passage for conveying elastic fluid from the high pressure turbine section to the ring of intermediate 24. Connected to the 80 outer casing 22 is an exhaust housing comprising two sections 26 and 27, one on each side of the machine. The two sections merge into each other to form an exhaust conduit 28. In the present instance they 85 are shown as being bolted to flanges 29 on the casing 22. Where the shaft 5 passes through the exhaust casing section, suitable packings 30 are provided to prevent leakage of air into the exhaust housing. 31 is a 90 ring bolted to the rotor drum 9 which serves to direct the elastic fluid from the ultimate ring of buckets on the drum 6 toward the ports of the low pressure turbine section.

In operation, elastic fluid entering by 95 means of conduit 16 is fed from the chest 14 to the high pressure turbine section comprising bucket rings 6 and intermediates 11, and after passing therethrough divides between the two parts of the low pressure section from which it exhausts to the exhaust housing sections 26 and 27. Since each part of the low pressure turbine section has to handle only half the elastic fluid, the buckets 7 and 8 can be kept within the necessary 100 limits as to length.

The pressure of the elastic fluid on the ring 19 carried by rotor 9 which produces a thrust toward the left, balances the pressure on the rotor which produces a thrust 110

toward the right. By this means end thrust in the machine can be substantially eliminated.

By the above described arrangement I obtain a very short compact turbine capable of handling efficiently in the low pressure end a large volume of elastic fluid. As will be noted there are in substance three concentric passages for handling the fluid, first the passage through the high pressure turbine section, second, the passage between the inner and outer casing 10 and 22, and third, the exhaust housing, and it is due to this that I am enabled to greatly diminish the shaft length. Since the elastic fluid chest 14 directly surrounds the casing 10 no extra length is required for this, and the bringing of the conduit or conduits 16 directly through the exhaust housing 26 and outer casing 22 to the chest 14 greatly simplifies the piping arrangement. It will also be noted that the shaft on both sides of the machine passes out of the turbine casing at points of low pressure so that no high pressure packings are required at these points. Also by having the exhaust housing sections formed separate and bolted to the casing 22, they can be readily turned to any angle so as to discharge the exhaust fluid downward, as shown, to one side, or upward as may be found desirable in any particular installation.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In an elastic fluid turbine, the combination of a shaft, a high pressure turbine section having its moving elements carried by the shaft, a divided low pressure turbine section having its two moving parts located one on each side of the high pressure section, and a stationary housing for the turbine which surrounds the high pressure and low pressure sections and carries the stationary elastic fluid directing elements for all said sections, said housing embodying an inner and an outer casing wall between which is an annular conduit for conveying elastic fluid to one of the low pressure parts, and an exhaust housing surrounding said

stationary housing and having a single exhaust outlet.

2. In an elastic fluid turbine, the combination of a shaft, a high pressure turbine section having its moving elements carried by the shaft, an inner casing surrounding said moving elements, stationary elements carried by the inner casing for directing fluid to the moving elements, a divided low pressure turbine section having its moving parts located on opposite sides of the high pressure section, an outer casing, stationary elements carried thereby for directing fluid to the said moving parts, the space between said inner and outer casings forming conduits, and an exhaust housing connected to the outer casing and at least partially surrounding it, whereby said exhaust housing, outer casing and inner casing are concentric.

3. In an elastic fluid turbine, the combination of a shaft, a high pressure turbine section having its moving elements carried by the shaft, an inner casing surrounding said moving elements, stationary elements carried by the inner casing for directing fluid to the moving elements, a divided low pressure turbine section having its moving parts located on opposite sides of the high pressure section, an outer casing, stationary elements carried thereby for directing fluid to the said moving parts, and an exhaust housing comprising two sections which are bolted to and surround the outer casing, said exhaust housing sections merging into each other and having a common exhaust conduit.

4. In an elastic fluid turbine, the combination of a shaft, a high pressure turbine section having its moving elements carried by the shaft, an inner casing surrounding said moving elements, stationary elements carried by the inner casing for directing fluid to the moving elements, a divided low pressure turbine section having its moving parts located on opposite sides of the high pressure section, an outer casing, stationary elements carried thereby for directing fluid to the said moving parts, an exhaust housing connected to the outer casing and at least partially surrounding it into which said low pressure sections exhaust, said exhaust housing having a single discharge outlet, a motive fluid chest for the high pressure turbine section, and a conduit which extends radially through said casings for conveying motive fluid thereto.

In witness whereof, I have hereunto set my hand this 13th day of October 1917.

JOHN H. DORAN.
